UNITED STATES PATENT OFFICE.

FRANK H. BANCROFT, OF GARDNER, MASSACHUSETTS, ASSIGNOR TO P. DERBY & COMPANY, OF GARDNER, MASSACHUSETTS, A CORPORATION OF MASSACHUSETTS.

AUTOMATIC TURNING-MACHINE.

1,400,013.

Specification of Letters Patent.

Patented Dec. 13, 1921.

Application filed October 21, 1918. Serial No. 259,103.

To all whom it may concern:

Be it known that I, FRANK H. BANCROFT, a citizen of the United States of America, and resident of Gardner, in the county of 5 Worcester and State of Massachusetts, have invented new and useful Improvements in Automatic Turning Machines, of which the following is a specification.

This invention relates to machines having 10 receivers or magazines through which stock is supplied and more particularly to automatic wood-turning machines of the type disclosed in my former application Sr. No. 119,145, filed September 8, 1916, for improvements in automatic turning machines.

The machine described in my former application comprises a rotatable carrier carrying a circular row of opposed head and tail spindles, the carrier being mounted to 20 rotate about an axis concentric with the circular row of spindles, means to rotate the carrier about its axis and to rotate the head spindles about their respective axes, a magazine to which rectangular blocks of wood or 25 other stock is supplied, means to bore the ends of the stock to receive the spindles while the stock is in the magazine, mechanism to transfer the stock from the magazine to the pairs of spindles at one position in 30 their path of revolution about the axis of the carrier, a plurality of cutters adjacent the said path of revolution adapted successively to act upon the stock as the carrier brings the stock into the regions thereof, and means 35 to deliver the turned articles from the machine.

The object of the present invention is to provide means for holding the stock in position in the magazine while the boring tools 40 operate on the opposite ends of the stock to prepare the stock to be picked up by the spindles and to prevent the stock from turning or otherwise moving while being bored. A secondary object is to position the stock 45 in the magazine just prior to its being transferred to the spindles by the feeding means so that the stock will occupy a definite position with respect to the feeding means when picked up thereby.

50 In the accompanying drawings,—

Figure 1 is a front elevation of a portion of the machine disclosed in my aforesaid application, showing the subject matter of the present invention applied thereto;

55 Fig. 2 is a side elevation, viewed from the

right of Fig. 1, of the magazine, feeding mechanism, and my new means for holding the stock in position in the magazine;

Fig. 3 is a front elevation on enlarged scale of the means for holding the stock in 60 position in the magazine;

Fig. 4 is a side elevation on enlarged scale of the holding means;

Fig. 5 is a detail view showing the cross-sectional shape of the magazine throughout 65 its central and upper portions; and

Fig. 6 is a similar view showing the cross-sectional shape of the magazine at the lower end.

The machine illustrated in part in the figures, which is similar to that disclosed in my aforesaid application, comprises in general a frame 1 carrying upright arms 2 and 3 which carry the cutters (not shown), a magazine M mounted on brackets 4 and 5, feeding mechanism designated generally by the reference character F, boring tools 6 and 7 including bits 8 and 9, the boring tools being arranged to rotate the bits and to reciprocate the bits into and out of a piece of stock 80 in the lower end of the magazine, and brackets 10 and 11 for mounting the boring tools on the frame of the machine. The magazine M comprises two channel members 12 and 13 having the cross-sectional shape shown 85 in Fig. 5 throughout their central and upper portions and having their forward flanges cut away at the lower end as indicated at 14 in Figs. 2 and 6. The channel members 12 and 13 have flanges 15 and 16 90 at the lower ends to support the blocks of stock S in the magazine and to prevent the stock from falling out through the bottom of the magazine. The channel members 12 and 13 are supported on the brackets 4 and 95 5 by means of bolts 17.

The mechanism for feeding the blocks from the magazine to the spindles of the machine comprises a pair of jointed arms rotatably supported on the shaft 18, each pair of arms comprising an upper portion 19 and lower portion 20 pivotally connected together. The lower arms 20 are provided with V-shaped carriers 21 adapted to push the lowermost piece of stock from the magazine and transfer it to the spindles (not shown). As shown in Fig. 1 the V-shaped carriers 21 are disposed in planes lying just inside the channel members 12 and 13 of the magazine so that they do not engage the 110

magazine as they are moved to the right from the position shown in Fig. 2 to push a piece of stock from the magazine through the opening 14.

5 The arms 20 are connected together at their free ends by means of a shaft 22, and the shaft 22 is connected to cam mechanism 23 so as to control the movement of the arms 20 in their course of oscillation to and fro between the magazine and the spindles. The left-hand arm 19 (Fig. 1) is connected to an eccentric 24 on shaft 25 through the connecting link 26 so as to be oscillated to and fro about the shaft 18. The cam mechanism 23 and eccentric 24 coöperate to oscillate the arms 19-20 and to control the path of movement of the carrier 21. This mechanism is fully described in the aforesaid application and it will be sufficient for the 10 purpose of this application to state that the carrier 21 in moving from the spindles to the position shown in Fig. 2 passes under the lowermost block in the magazine, thence upwardly to the position shown in Fig. 2, and thence passes forwardly to push the lowermost block out of the magazine through the opening 14 and transfer it to a pair of spindles.

15 The boring mechanism 6 and 7 is arranged to bore openings in the opposite ends of each block of stock while it is in the lowermost position in the magazine, the boring bits 8 and 9 being arranged to pass through openings 27 and 28 in the channel members 12 and 13 of the magazine. When operating at high speed and upon small pieces of stock there is a tendency for the pieces of stock to be rotated or otherwise moved in the magazine by the boring tools. In order to overcome this tendency I have provided means for holding the blocks in position while being bored or otherwise operated upon by end-forming tools.

20 The preferred embodiment of my improved means for holding the stock in position while being acted upon by the end-forming tools comprises two elongate members 29 slidable up and down along the opposed faces of the magazine supports immediately in the rear of the stock in the magazine. These elongate members are provided with inclined faces 30 at their lower ends adapted to coöperate with inclined members 31 to force the members 29 25 against the face of the lowermost piece of stock when the members 29 are moved downwardly as shown in Figs. 3 and 4. When the members 29 are moved upwardly the lower portions are withdrawn from in front of the lowermost block, as shown in Fig. 2, so that the block may be moved out through the opening 14. The arms 29 are provided with vertical slots 32 near their upper ends which fit over pins 33 threaded into the 30 magazine supports, the pins 33 serving as

guides for the members 29 as the members are reciprocated up and down. The pins 33 carry oscillatory blocks 34 at their outer ends and the members 29 carry plates 35 having flanges 36. Mounted in the blocks 34 are rods 37 which extend through openings 38 in the flanges 36. A coiled compression spring 39 is mounted on the rod 37 between the blocks 34 and the flanges 38 so as to urge the members 29 downwardly. Fast to the shaft 18 are collars 40 having dogs 41 pinned or otherwise secured to their outer faces so as to engage the lower ends of the members 35 to raise the members 29 against the action of the springs 39.

35 The operation of the mechanism is as follows:—

Blocks of stock S are fed into magazine M through which they move downwardly by gravity. When a block reaches the lower end of the magazine and rests on the flanges 15 and 16, the members 29 are forced downwardly by springs 39 into the position shown in Figs. 3 and 4 rigidly to clamp the stock in the magazine while the boring tools operate on the stock. The members 29 are then moved upwardly by the dogs 41 into the position shown in Fig. 2 and are held in this position while the lowermost piece of stock is pushed from the magazine and transferred to the spindles by the carrier 21. The next piece of stock then drops to the bottom of the magazine and the operation is repeated. The shaft 18 is oscillated to and fro by means of arms 19, which are keyed to the shaft; although it will be understood that the shaft may be rocked to and fro in synchronism with the feeding mechanism and boring mechanism by any suitable means. Owing to the rearward inclination of the rods 37 the springs 39 not only serve to force the members 29 downwardly but they also serve to hold the members 29 in contact with the inclined members 31 at all times.

40 I claim:

1. In a turning machine having a receiver to which pieces of stock are successively supplied prior to being fed to the spindles, the combination with said receiver of means for shaping the end of each piece of stock to interfit with a spindle, and reciprocatory means for automatically clamping each piece of stock in the receiver while being shaped by said first means, said last means being arranged to reciprocate approximately longitudinally of the magazine.

2. In a turning machine having a magazine in the form of an elongate channel with an opening therein through which pieces of stock may be fed to the spindles of the machine, the combination with said magazine of means for shaping the ends of the pieces of stock to interfit with the spindles, a member recurrently movable into and out of

position before said opening, and a second member arranged to engage said first member in such manner as to force it over against the stock so as to hold the stock 5 in position while being acted upon by said first means.

3. An automatic machine of the character described comprising a magazine, the magazine having an elongate channel and having an opening in one side so that pieces 10 of stock may be fed longitudinally through the magazine and thence laterally through the side opening, a tool for operating upon each piece of stock when it comes into position before said opening, and means recurrently movable into and out of position before said opening for temporarily clamping the stock in position in the magazine 15 while being acted upon by said tool.
- 20 4. An automatic machine of the character described comprising a magazine, the magazine having an elongate channel and having an opening in one side so that pieces of stock may be fed longitudinally through the magazine, and thence laterally through the side opening, a tool for operating upon each piece of stock when it comes into position before said opening, a member recurrently movable into and out of position before said 25 opening, and a second member arranged to engage said first member in such manner as to cam it over against the stock so as to 30

hold the stock in position while being acted upon by said tool.

5. In a machine of the character described 35 a magazine, the magazine having an elongate channel and having an opening in one side so that pieces of stock may be fed longitudinally through the magazine and thence laterally through the side opening to 40 the spindles, means for shaping the ends of the stock to interfit with the spindles, said means being operative when the stock comes into position before said opening, a cam member arranged to reciprocate into and out 45 of position in front of said opening, a second cam member arranged to engage the first cam member and cam it over against the stock in the opening so as to hold the stock in position while being acted upon by 50 said shaping means.

6. In a turning machine having a magazine through which pieces of stock are fed, means for shaping stock to interfit with spindles, an opening in the magazine 55 through which the stock is ejected after shaping, and means movable in two dimensions to first close the opening and then clamp the lowest piece of stock in position for said means to operate thereon. 60

Signed by me at Gardner, Massachusetts, this eleventh day of October, 1918.

FRANK H. BANCROFT.
